ATTORNEY.

UNITED STATES PATENT OFFICE.

ALONZO E. CHAPMAN, OF PLACERVILLE, CALIFORNIA.

POP-GUN.

SPECIFICATION forming part of Letters Patent No. 653,376, dated July 10, 1900.

Application filed May 2, 1900. Serial No. 15,272. (No model.)

To all whom it may concern:

Be it known that I, ALONZO E. CHAPMAN, a citizen of the United States, residing at Placerville, in the county of El Dorado and 5 State of California, have invented certain new and useful Improvements in Pop-Guns, of which the following is a specification.

My invention relates to improvements in pop-guns, the object of my invention being 10 to provide a toy of this character which shall be cheap and simple in construction and which can be used with any small pieces of paper instead of with the cork stopper used in connection with the ordinary form of pop-gun.

15 My invention therefore resides in the novel construction, combination, and arrangement of parts for the above ends hereinafter fully specified, and particularly pointed out in the claims.

20 In the accompanying drawings, Figure 1 is a perspective view of the pop-gun. Fig. 2 is a vertical section of the same, the plunger being shown in side elevation. Fig. 3 is a perspective view of the plunger removed. Fig. 25 4 is a perspective view of the flexible disk which serves to close the exit of air from the chamber of the pop-gun. Fig. 5 is a bottom plan view of the holder for the paper. Fig. 6 is a perspective view of the same detached 30 from the pop-gun looking at the upper side thereof.

Referring to the drawings, 1 designates the cylinder of the pop-gun, which is turned outward at its upper end to form a flange 2, serving 35 as a rest or abutment for the hand when depressing the plunger, said cylinder having at its lower end a flange 3. On said flange 3 is crimped the holder 4, and a disk 5 of thin flexible material is clamped between said 40 holder and said flange 3. Said holder 4 has its central part 6 depressed to form a support for a strip of paper which is adapted to be passed through slits 7, cut on each side of said central part and separating it from the 45 holder 4.

48 8 is a plunger having formed thereon at its top a suitable knob 9, by means of which to retract or depress the plunger. The lower end of the plunger is formed with a flexible 50 washer 10, adapted to fit snugly within the cylinder 1.

The strip of paper having been inserted in

the holder from one side or the other through the slits 7, the plunger is depressed, thereby compressing the air in the chamber of the 55 cylinder. The disk 5 has a central hole 11, and the compression of the air forces the free edge of said hole down upon the paper, thus preventing the escape of air from the cylinder. The central portion 6 of the holder has also a 60 somewhat larger circular aperture 13, and thus continued compression of the air in the chamber of the cylinder will rupture the strip of paper contained in the holder and permit the compressed air to escape from the aperture 65 thus formed and through the circular hole 13 in the central portion of the holder, and this escape of air will be accompanied by a violent explosion on account of the extreme compression to which the air has been subjected. The extent of this compression will 70 vary with the tensile strength of the paper.

The advantages of my construction are that the device is complete in itself and does not necessitate the use of a cork stopper, which 75 is very liable to be lost and which if lost is comparatively expensive and inconvenient to replace. With my improved pop-gun, however, any ordinary paper may be used if cut up into pieces of suitable sizes. Furthermore, a more violent explosion can be produced than with the common form of pop-gun, as the extent of compression is limited 80 only by the tensile strength of the paper and the strength of the device itself. 85

I claim—

1. In a pop-gun, the combination with a suitable cylinder, and a plunger, of a holder for a strip of paper, and means for automatically closing the exit of air upon depression 90 of the plunger, whereby further compression of the air ruptures the paper and produces an explosion, substantially as described.

2. In a pop-gun, the combination of a cylinder, a plunger therein, a holder mounted at 95 the end of the cylinder, and adapted to support a strip of paper thereon, and a flexible disk over said paper so supported, and arranged to be depressed upon said paper by the operation of the plunger, and make an 100 air-tight joint thereon whereby the compression of the air by further operation of the plunger ruptures the paper and produces an explosion, substantially as described.

3. In a pop-gun, the combination of a cylinder, a plunger therein, a holder mounted on the end of the cylinder having a depressed, apertured central portion with side slits through which a piece of paper can be inserted, and means whereby the depression of the plunger automatically renders the central chamber air-tight, whereby further depression thereof ruptures the paper and causes an explosion, substantially as described.
4. In a pop-gun, the combination of a cylinder, a plunger therein, a holder mounted on the end of the cylinder having a depressed

apertured central portion with side slits for permitting the pieces of paper to be inserted and rest upon said central portion, and a flexible apertured disk mounted in the cylinder above said depressed portion, substantially as described.

In witness whereof I have hereunto set my hand in the presence of two subscribing witnesses.

ALONZO E. CHAPMAN.
